UNITED STATES PATENT OFFICE.

THERON R. WOODRUFF, OF MENTOR, OHIO.

DESIGN FOR A FRUIT-BASKET.

SPECIFICATION forming part of Design No. 26,389, dated December 8, 1896.

Application filed October 26, 1896, Serial No. 610,158. Term of patent 7 years.

To all whom it may concern:

Be it known that I, THERON R. WOODRUFF, a citizen of the United States, residing at Mentor, in the county of Lake and State of Ohio, have invented and produced a new and original Design for Fruit-Baskets, of which the following is a specification, reference being had to the accompanying drawings, in which said design is illustrated.

Figure 1 is a perspective view of a fruit-basket, showing my design. Fig. 2 is a side elevation thereof, and Fig. 3 is an end elevation.

The leading feature of my design consists in the contour of the basket coupled with its surface finish and appearance as it is seen when viewed in elevation or perspective.

A represents the body of the basket, which has straight plain sides 2 with a smooth and even surface, and ends 3, which are likewise plain, smooth, and even on their surface, and

said sides and ends are inclined inward from top to bottom at like angles and meet at right angles at the corners 4, which are flush with both sides and ends. The bottom 5 and the top or cover 6 likewise are distinguished by plain, straight, and smooth surfaces, and the top of the basket is decorated with open corners and a central arch or bow B, extending over the top of the basket from side to side and down across both sides thereof midway between its ends.

What I claim is—

The design for a fruit-basket, substantially as herein shown and described.

Witness my hand to the foregoing specification this 15th day of October, 1896.
